Patented May 22, 1956

177,726

DRAPERY HOOK

James Leonard Golding, Chicago, Ill.

Application December 23, 1955, Serial No. 39,464

Term of patent 14 years

(Cl. D21—1)

Fig. 1

I claim:

The ornamental design for a drapery hook, substantially as shown.
